COIN SELECTOR

John Gottfried, St. Louis, Mo., assignor to National Slug Rejectors, Inc., St. Louis, Mo., a corporation of Missouri

Application April 21, 1941, Serial No. 389,539

2 Claims. (Cl. 194—97)

This invention relates in general to coin selectors and more specifically to improvements in coin selecting apparatus of the class wherein inserted coins, under the influence of gravity, are selected by size, conductivity, and resilience.

Previous coin selectors of this character were necessarily large in size in order to provide proper paths and trajectories for coins inserted therein and thus were relatively expensive to construct.

In the present invention, by the introduction of new and novel improvements and construction to be hereinafter described, in addition to attaining increased efficiency, the apparatus may be confined in a relatively small space, which fulfills one of the principal objects of the invention.

A further object of the invention is the provision of a sensitive adjustment whereby spurious coins having extremely close physical characteristics to that of genuine coins are efficiently separated.

Another object of the invention is the provision of a simple and effective means for scavenging defective or spurious coins retained in the device.

A further object of the invention is the provision of a novel pole piece through which a single permanent magnet of relatively small size is utilized to test coins for conductivity.

With these and other objects in view, the invention consists of the novel combination and arrangement of elements described, one embodiment of which is illustrated in the accompanying drawings, in which:

Fig. 1 is a side elevation of the coin selector.

Fig. 2 is the opposite side elevation of the selector shown in Fig. 1.

Fig. 3 is an enlarged sectional view of the coin selector taken substantially through the section line *a—a*, Fig. 1.

Fig. 4 is the same as Fig. 3 with certain elements in their displaced positions.

Fig. 5 is a sectional view of Fig. 1 taken substantially through section line *b—b*, Fig. 3, exposing the internal parts of the selector in their normal positions.

Fig. 6 is a sectional view of the coin selector as shown in Fig. 1 taken through section line *c—c*, Fig. 3.

Fig. 7 is an enlarged perspective view of the pole piece.

Fig. 8 is an enlarged perspective view of the magnet.

Referring to Fig. 1, the frame, or main plate,

1 is a support for all of the elements of the coin selector. Gate 2 is pivotally mounted to the main plate at pivot lugs 3 and 4 and normally urged in close proximity to plate 1 by spring 5 coiled about pivot lug 3, having its opposite ends retained by the plate 1 and the face of the gate 2 respectively secured to the plate, thus providing a coin passageway between the inside surface of the gate 2 and the inside surface of the 10 main plate 1.

An adjustable coin runway 6 is secured to the lower end of the gate 2 by screws 7—7, a projection of which provides a lower surface in the coin passageway between the gate 2 and the 15 plate 1, over which coins of proper diameter are caused to pass under the influence of gravity.

Fig. 7 shows a paramagnetic pole piece 8 removed from the rejector and illustrates the 20 poles 8N and 8S integral therewith.

Referring to the sectional view, Fig. 3, pole piece 8 is secured to the main plate 1 by stud 32 and screw 34 and has its two poles 8N and 8S projecting through apertures in the main 25 plate 1, the said poles positioned in the same plane as the inside surface of the plate. Magnet 9 is positioned opposite pole piece 8 by offset bracket 10 secured to the plate 1, shown in Fig. 1. The two poles of the magnet 9 are similar 30 in size and positioned directly opposite the poles of the pole piece 8 and spaced sufficiently apart to provide free passage of coins there-between. Thus, two paths of intense flux density are provided across the coin passageway. The projection 35 11, Fig. 3, of the adjustable runway 6 serves as a bottom surface for the aforementioned coin passageway.

Coin separators prior to this invention utilize 40 two separate magnets positioned opposite each other in order to obtain sufficient flux density to properly test the conductivity of coins. In the present invention it has been found that the novel construction of the pole piece 8, above described, provides two concentrated paths of 45 magnetic flux originating from a single small magnet, which concentrated flux paths are used to test the conductivity of coins passed therethrough.

Anvil 12, secured to the inside surface of the 50 plate 1, Fig. 3, is used to test the resiliency of coins impinged thereupon and will be herein-after described.

Hopper 13, Figs. 1 and 3, is provided to serve as one of the exit passageways for rejected coins. Lateral guide 14, integral with the main

plate, is positioned in the path of certain rejected coins to displace them into the rejection hopper.

Fig. 5 shows an internal view of the plate 1 with the various essential coin testing elements in their normal relative positions. The dotted line starting at the point of coin entry at the upper left-hand portion of the figure and continuing through the device describes the path of travel of a normally acceptable coin to the acceptance outlet at 15.

A counterweighted rocker 16 is pivotally mounted to the main plate at 17 (best shown in Figs. 2 and 5), and provided with projections 18 and 19 extending into the coin entrance passageway for the purpose of rejecting undersized coins. The projections 18 and 19 are spaced to provide free passage there-between of coins having diameters less than that of acceptable coins. Thus, if an undersized coin is deposited in the entrance passageway it will pass between the projections 18 and 19 and impinge upon the lateral guide 14 and fall into the rejection hopper 13, shown in Figs. 3, 4, and 5.

Wiper blade 21, Fig. 5, is pivotally mounted to the main plate 1 at 22 and is normally urged into the position shown by spring 27 to be hereinafter described. The lower edge of the wiper blade 21 is normally positioned with respect to projection 11 to permit free passage thereby of coins having proper diameter. It is apparent that when a coin is deposited having a diameter larger than that of an acceptable coin it will lodge between the blade 21 and projection 11. Means for dislodging coins thus arrested will be hereinafter described.

The lateral abutment 23 is formed from an integral projection from the back plate 1 as shown in Figs. 3 and 5 and is provided to impart lateral movement to rejected coins having relatively high conductivity, the action of which will be apparent from the following description.

Referring to Fig. 5 and assuming that an acceptable coin is deposited into the passageway at the upper left-hand opening in the device, it will first impinge upon projections 18 and 19 and, by the action of gravity, the rocker 16 will rotate in a clockwise direction around the pivot 17 and deliver the moving coin into the aforementioned passageway upon the sloping projection 11 at a predetermined velocity, whereupon it will start its downward sloping descent rolling upon the projection 11. During this latter movement the coin will intercept the two paths of concentrated magnetic flux supplied by the magnet 9 and the poles 8N and 8S of the pole piece 8, whereupon the velocity of the coin will be retarded in proportion to its conductivity. As soon as the coin approaches its position of free trajectory at the right-hand end of the projection 11, the action of gravity will impart an increased downward vertical component of motion to the coin, and thus the coin will move in a free trajectory with both horizontal and downward vertical components of motion. Whereupon the coin will strike the surface of the anvil 12 at a predetermined point 24 and rebound in a manner determined by its resilience in an arcuate path over an acceptance barrier 25 to the acceptance outlet at 15.

It will now become apparent that because of the relatively short coin trajectory provided (not more than approximately two and one half times the diameter of acceptable coins) the position of the lower end of the projection 11 with relation to the concentrated flux paths and with relation

to the surface of the anvil 12, is extremely critical.

Therefore, longitudinal adjustment has been provided for the projection 11 by means of screws 5 1—7 and corresponding elongated holes in the runway 6, shown in Fig. 1. Through the action of this adjustment accurate differentiation between spurious coins having conductivity and resilience very close to the conductivity and resilience of acceptable coins may be accomplished even though the guided path and the free trajectory path of the coin are relatively short.

Thus one of the principal features of the present invention resides in the adjustment of the projection 11 with relation to the pole pieces 8N and 8S and the anvil 12, shown in Fig. 1.

In contradistinction to this invention, prior coin selectors, not having the previously-mentioned adjustable feature, were necessarily required to provide relatively long free coin trajectories, whereby the coin to be tested would be relatively free of horizontal components of motion prior to being impinged upon an anvil.

When coins having conductivity less than acceptable value are inserted in the device, it is apparent that the slowing effect of the magnets will cause the coin to strike the anvil 12 at a point higher than 24, and thus the coin will either rebound against abutment 23, Fig. 5, and be rejected, or fail to rebound sufficiently far to clear the barrier 25, and thence fall into the rejection passageway 26.

When a coin having greater conductivity than the conductivity of an acceptable coin is passed through the device, the magnetic flux will retard the velocity of the coin to a degree less than that of an acceptable coin and its trajectory upon leaving the projection 11 will be sufficiently short to cause the coin to strike the abutment 23, whereby it will be laterally deflected into the rejection hopper 13, shown in Figs. 4 and 6.

A further feature of the invention is the novel simplified means employed in dislodging deformed coins or other debris which may have been deposited in the device and lodged in the coin passageway.

Referring to Fig. 2, the scavenging operating lever 27 is pivotally mounted at one end to the main plate 1 at 28 and retained in close proximity with the main plate by virtue of a pair of offset ears 29—29, extending through an elongated aperture 30 in the main plate 1. The lever 27 is normally urged in its upward position, shown in full lines, Fig. 2, by contact with spring 31, which is retained in position by studs 32 and 33, better shown in Fig. 3.

Wiper blade 21, Fig. 5, is pivotally mounted to the main plate 1 adjacent to the coin entrance passage at 22 and is provided with an integral projection 35 extending at right angles to the blade through an arcuate aperture 36.

The projection 35 normally lies in the downward path of a downward extension 37 of the lever 27, shown in Fig. 3. Lever 27 is also provided with a lateral cam projection 38 which normally extends above and over a horizontal surface 39 of the gate 2, shown in Figs. 1 and 3. Thus, when the scavenger lever 27 is moved into a downward position, as shown in dotted lines Fig. 2, the extension 37 of lever 27 will contact the projection 35 of the wiper blade and cause the wiper blade to move clockwise about its pivot to a downward position, as shown in Fig. 6, which action will contact and dislodge any paramagnetic coins or materials suspended by the poles

8N—8S. When the wiper blade is held in its downward position, as shown in Fig. 6, it is obvious that any coins deposited will be blocked from traveling through the testing passageway and be immediately by-passed by virtue of the projection 14 into the rejection hopper 13, and be returned to the depositor.

In addition to the aforesaid, during the downward movement of the lever 27, the cam projection 38, Fig. 3, will engage the surface 39 of the gate 2, shown in Fig. 3, and move the gate about its pivots 3 and 4 to its outward position with projection 11 out of contact with the main frame, shown in Fig. 4, thus dislodging any coins or other debris which may have been lodged between the gate and the main frame. The scavenging operation, in addition to permitting articles retained therein to be cleared from the device, provides a blocking action, because of the position assumed by the wiper blade 21 when in its scavenged position, to prevent the possibility of fraudulent acceptance of defective coins during the scavenging operation.

Having described my invention, I claim:

1. An apparatus for selecting coins having different physical qualities, comprising a casing, a coin entrance in said casing, a coin runway, means located between said coin entrance and coin runway for causing a coin to reach said

runway at a predetermined velocity, a magnet located in the path of coins moving along said runway, said runway having a terminus located in a position to permit a coin to fall by gravity, while the coin is still within the influence of said magnet, into a free trajectory acceptance path or a free trajectory rejection path, and means to adjust the position of said runway longitudinally of its length to thereby adjust said runway terminus with relation to the magnet.

2. An apparatus for selecting coins having different physical qualities comprising a casing, a coin entrance in said casing, a coin runway, means located between said coin entrance and coin runway for causing a coin to reach said runway at a predetermined velocity, a magnet located in the path of coins moved along said runway, said runway having a terminus located in a position to permit a coin to fall by gravity, while the coin is still within the influence of said magnet, into a free trajectory acceptance path or a free trajectory rejection path, and means to adjust the distance between the magnet and the runway terminus along the path of the coin as it travels in said runway, to regulate the distance between said magnet and the runway terminus.

JOHN GOTTFRIED.
